S. P. KAY.

TOOL FOR SETTING THE TEETH OF CIRCULAR SAWS.
APPLICATION FILED SEPT. 8, 1919.

1,349,614.

Patented Aug. 17, 1920.

UNITED STATES PATENT OFFICE.

SAMUEL P. KAY, OF ROCHESTER, NEW YORK, ASSIGNOR OF ONE-THIRD TO RUFUS P. WOLF, ONE-THIRD TO ANNIE K. ROWND, AND ONE-THIRD TO ARETHUSA KAY, ALL OF ROCHESTER, NEW YORK.

TOOL FOR SETTING THE TEETH OF CIRCULAR SAWS.

1,349,614.

Specification of Letters Patent. Patented Aug. 17, 1920.

Application filed September 8, 1919. Serial No. 322,447.

To all whom it may concern:

Be it known that I, SAMUEL P. KAY, a citizen of the United States, residing at Rochester, in the county of Monroe and State of New York, have invented certain new and useful Improvements in Tools for Setting the Teeth of Circular Saws, of which the following is a specification.

The object of this invention is to provide a new and improved method and tool for setting the teeth of circular saws.

This and other objects of this invention will be fully illustrated in the drawing, described in the specification and pointed out in the claims at the end thereof.

In the accompanying drawing:

Figure 1 is a side elevation of the saw setting tool as it appears when clamped to the adjustable guide of the saw table.

Fig. 2 is a top plan view of the tool as shown in Fig. 1.

Fig. 3 is a cross section of the arm and pivot pin of the tool, showing how the clamp holds the tool in place on one side of the guide and in line with the saw.

Fig. 4 is a sectional view of the saw setting roller.

Fig. 5 is a sectional view of a modified form of the roller.

Fig. 6 is a detail view of a section of a grooving saw.

Fig. 7 is a sectional view of one of the teeth of a grooving saw after being swaged, the section being taken on the line 7-7 of Fig. 6.

In the several figures of the drawing, like reference numerals indicate like parts.

The tool comprises the arm 1 which is made up of flat bar stock and has the handle 2 formed on one end thereof. The other end of the arm 1 has a bracket 3 fastened thereto to form a fork 4 thereon in which the saw setting roller 5 is mounted to rotate. For this purpose the end of the bracket 3 and the end of the arm have the pivot pin 3^a supported between them on which the roller 5 is adapted to rotate.

The bracket 3 is fastened to the arm 1 by means of suitable bolts or rivets 6 which project through the bracket near the inner end thereof and pass into the arm 1. A bearing 7 is provided in the arm 1 and bracket 3

at the point where the bracket is fastened to the arm, in which bearing the bolt 8 is mounted to rotate. This bolt is preferably provided with the enlarged, flat head 8^a which projects out from the side of the arm 1 opposite to the bracket 3. The middle portion of the bolt 8 is adapted to rotate in the bearing 7 while the threaded end thereof, which is of reduced diameter, projects out therefrom to receive the nut 9 by means of which the bolt 8 is held in place in the bearing 7. The reduced threaded end of the bolt provides the shoulder 10 thereon against which the nut 9 is tightened so as not to interfere with the easy rotation of the bolt in the bearing 7. For this reason the shoulder 10 is formed slightly beyond the outside of the bracket 3 so that the inner face of the nut 9 cannot come into contact therewith and cause friction therewith, which would interfere with the free rotation of the bolt 8 in the bearing of the arm 1.

Any one of the many forms of clamps, one of which is indicated by reference numeral 11 in Figs. 1, 2 and 3, may be used to clamp the tool in place on the guide 12 of the saw table 13. The clamp 11 is hooked over the guide 12 and its stationary member 14 is placed in contact with the outer face of the nut 9 carried on the bolt 8. The adjustable member 15 of the clamp is then screwed against the outside of the guide 12 so as to force the arm 1 toward the inner side of the guide and securely hold the large head 8 of the bolt against the guide which then forms a stationary pivot around which the arm 1 is adapted to swing.

In order that the handle of the arm can be easily moved up or down, a portion of the arm with the handle 2 thereon is bent out away from the guide 12 so that it can be easily taken hold of by the operator.

The roller 5 has the beveled perimeter by means of which the saw teeth are alternately bent outwardly on either side during the process of setting the teeth of the circular saw with the tool heretofore described. This is done as follows:

The tool is first clamped against the guide 12 of the saw table 13 as shown in Figs. 1, 2 and 3. Then the guide 12 is moved over the saw table toward the cir-

cular saw until the distance between the center or periphery of the saw and the inner side of the guide 12 equals the distance between the beveled edge of the roller 5 and the inner side of the guide 12. The handle of the tool is then raised from the full line position to the dotted line position as shown in Fig. 1. In doing so the beveled edge of the roller 5 is brought into contact with the teeth of the saw and operates to bend the successive teeth of the saw in opposite directions to the left or right of the saw disk. That is, one tooth is forced over the bevel on the left hand side of the roller and bent to the left of the saw disk and the next tooth is forced over the bevel on the right hand side of the roller and thus bent toward the right of the saw disk until all of the teeth of the saw have been bent evenly and successively in an opposite direction. After the roller 5 has been held in contact with the circular saw during one of the revolutions, all of the teeth are set as above pointed out and the roller may be withdrawn from the saw by rocking the tool back into its inoperative position.

This process of setting a saw is performed on all saws of the cross cut type on which each tooth is formed in the form of a small triangle having equal sides such as are shown in the circular saw illustrated in Fig. 1. The teeth are set in this manner in order that the cut made by the saw will be wider than the thickness of the disk of the saw.

In the case of a grooving saw, the teeth of which are formed as shown in Fig. 6, the teeth are not set as above pointed out but are what is commonly called swaged.

For this operation the roller illustrated in Fig. 5 is used. Instead of being beveled this roller has a slightly curved perimeter provided thereon so that when it is brought in contact with the teeth in the same manner as described in connection with the beveled roller the points of the teeth are flattened out or swaged thereby, as illustrated in Fig. 7.

I claim:

1. In a tool for setting circular saws, the combination of an arm, a roller having a beveled edge on each side of the periphery thereof mounted to rotate loosely on one end of said arm, a pivot pin passing through said arm and projecting out on each side thereof, said pivot pin being loosely mounted in said arm, means to hold said pin in place in said arm, and means to clamp said pin against a stationary member to allow said arm to rock around said pivot pin as the center.

2. In a tool for setting circular saws, the combination of an arm, a roller having a beveled edge on each side of the periphery thereof mounted to rotate loosely on one end of said arm, a pivot pin passing through said arm and projecting out on each side thereof, said pivot pin being loosely mounted in said arm, means to hold said pin in place in said arm, means to clamp said pin against a stationary member to allow said arm to rock around said pivot pin as the center, and a handle formed on said arm, said handle being offset from said arm to facilitate the raising and lowering of said arm.

In testimony whereof I affix my signature
SAMUEL P. KAY.
